UNITED STATES PATENT OFFICE.

ERNEST FERRAN AND FRANCIS D. TWEEDDALE, OF SAN FRANCISCO, CALIFORNIA.

CALL-REGISTERING DEVICE FOR TELEPHONES.

1,135,887.

Specification of Letters Patent. Patented Apr. 13, 1915.

Application filed March 16, 1914. Serial No. 825,406.

To all whom it may concern:

Be it known that we, ERNEST FERRAN and FRANCIS D. TWEEDDALE, citizens of the United States, residing in the city and county of San Francisco and State of California, have invented a new and useful Improvement in Call-Registering Devices for Telephones, of which the following is a specification.

10 Our invention relates to registering devices for telephones wherein the electrically operated mechanism in nickel telephone boxes operates mechanical means for registering the number of switches obtained 15 through the telephone to which the said nickel box is connected, and the objects of our invention are first, to provide improved means for registering every switch or connection which is made through the telephone 20 to which the device is connected; and second, to provide improved means for registering calls where the desired connection or party is not obtained. We accomplish these 25 features by means of the device illustrated in the drawings forming a part of the present specification, wherein like characters of reference are used to designate similar parts throughout the said specification and drawings, and in which—

30 Figure 1 is a view of a nickel collecting box for telephones with the front portion thereof partly broken away, disclosing the registering disks rotatable in opposite directions, the armature which operates one of the disks, the spring contact which engages the token which is being returned to the subscriber, and the springs which retain the armature normally in a central position. Fig. 2 is a side view of the nickel box with 35 the side thereof and the inner plate removed, disclosing the arresting pins projecting through the frame, and the slot pressed within the said frame. Fig. 3 is a detailed broken view of the armature and the springs which normally retain it in a central position. Fig. 4 is a horizontal sectional view through the nickel box disclosing the arrangement of the coils and armature for returning the token to the subscriber or into 45 the box, and operating one of the registering disks, and the coil and armature for operating the refund registering device. Fig. 5 is a vertical sectional view taken on line X—X of Fig. 4 disclosing the manner in 50 which the registering disks are rotatably

mounted within the box. Fig. 6 is a broken detail view of the recording disks, the pawl and ratchet for operating the refund registering mechanism, and the pawl which prevents a return movement of the refund registering mechanism. Fig. 7 is a broken detailed view of a portion of the registering disks and the window in the front of the cover of the box. Fig. 8 is a diagrammatic view of the electrical circuit for operating the various parts of the device.

In telephones where a nickel or token box is used, the only means by which the number of switches obtained may be determined, is by the number of token in the box. Subscribers have discovered and invented various means of obtaining switches and operating the signals at the central station without using tokens.

In the present equipment, a base plate 1 is provided with a cover 2 having an upper slot 3 through which the nickel or token V is inserted. The frame 4 secured to the base plate 1 and within the cover 2, is provided with the impressed slot having the 80 inclined receiving portion 5, the curved passage 6 and the inclined return or refund portion 8 through which the token V is delivered through the lower slot 9 of the cover 2 and into a suitable receptacle 10. The 85 frame 4 is also provided with an aperture or collecting portion 7 through which the token is directed into the box when the desired telephonic connection has been obtained.

Within the box and secured to the frame 4, are the magnetic coils 12 and 14 and the centrally pivoted armature 16 insulated from the frame 4 by means of the insulating bearings 17 and 18. The armature 16 is normally retained in a central position by means of springs 19 and 20 which are also insulated from and secured to the frame 4. The lower ends of the springs 19 and 20 rest on the edge of the bearing 17 and slightly beyond the upper edge of the armature 16 so that when the said armature is operated by either coil 12 or 14 the end attracted will engage the spring on that side and be returned to normal position by 105 the said spring as soon as the said coil is deenergized.

Pins 24 and 25 are secured to the armature 16, the pin 25 being insulated therefrom, and project through apertures in the 110

curved portion 6 of the slot in the frame 4 in such a position that a token, of the correct size and shape in the said slot, will be retained by the said pins 24 and 25.

5 In the present state of the art when the party using the telephone desires to attract the attention of the operator for the purpose of making the desired connection, a token V is deposited in the slot 3 of the 10 cover 2 and rolling down the inclined portion 5 is delivered between the pins 24 and 25.

By referring to the circuit in Fig. 8 of the drawings, it will be observed that the 15 result will be as follows: The token V will close the circuit between the pins 24 and 25 and the current will then flow from the ground to the battery 27, line 28, lamp 29, line 30, line 31 to pin 24, which is electrically connected to the said line, token V, 20 insulated pin 25, line 32, line 33, frame 4 and ground to battery 27.

When the operator observes the light 29, the proper connections are made to the 25 party desired which have no connection with the present invention and are consequently not shown. If the desired connections are obtained by the calling party, the operator passes the key 35 and connects the 30 same with the battery 36. The current will then flow from the said battery 36 through the said key 35, line 37, line 30, coils 14 and 12, line 33 to the frame 4 and to the ground. The current flowing in the above direction 35 will cause the coil 12 to act on that side of the oscillating armature 16 and withdraw the pin 24 which will allow the token V to drop into the collecting portion of the slot on the inclined slide 40 of the cover piece 40 41 which incloses the slot impressed within the frame 4, through the slot 7 into the cash box within the cover 2. See Fig. 1 of the drawings.

While the current from the battery 27 is 45 sufficient to light the lamp 29 it is not sufficient to operate either coil 12 or 14.

If the party sought is busy or the connections for any reason not obtained, the operator moves the key 35 to the opposite direction and into contact with battery 36' which causes the current to flow in the opposite direction from that heretofore described when the token is to be deposited in the cash box. The current will then flow through 50 the hereinbefore mentioned lines and members and cause the coil 14 to attract the armature 16 on that side, thereby withdrawing the insulated pin 25 and allowing the token V to drop into the inclined portion 8 of the slot in the frame 4 which will deliver the said token through the lower slot 9 in the cover 2 and into the receptacle 10 thereon from which it may be recovered by the person who deposited it.

65 Thus far the description of the operation

has referred to the present method of registering the number of calls or switches obtained from any one telephone.

Referring to the circuit in Fig. 8, it will be observed that if the subscribers end of the line is grounded through the token box, not necessarily through the coils 12 or 14, or the pins 24 and 25, the lamp will be lighted and the switch may be obtained without the deposit of a suitable token to be collected by the operator in order to register the switch. The operator has no means from which to determine whether or not a proper token has been deposited, and if there is no token between the pins, no token will be collected to register that switch.

We propose to provide means whereby every switch called for will be registered whether obtained or not. If the desired switch is not obtained the passage of the refunded coin will electrically connect means for registering such refund. The total number of switches registered minus the refunds registered will then indicate the number of switches or calls obtained except when 90 the signal at the central station has been operated by other means than the deposit of a suitable token and the party is not obtained then the central operator in operating the token refunding mechanism will register a switch obtained. The above means to be operated by the coils and the armature which are at present used for the purpose of collecting or returning the token.

We have provided an insulated extension 100 22 to the armature 16, said extension 22 being pivotally connected to a rod 42 and the other end of the said rod being in turn pivotally connected to a lever 43 loosely mounted upon the sleeve of the rotatable 105 disk 47 on the shaft 44. The upper end of the lever 43 is provided with a suitable pawl 45 which engages the teeth of the ratchet 46 secured to the disk 47. A pawl 48, pivotally secured to the frame 4, is adapted to 110 prevent a return movement of the said ratchet 46.

By referring to Figs. 1 and 4 of the drawings, it will be observed that when the armature 16 is attracted by either the collecting 115 coil 12 or the refunding coil 14, the said movement will, by means of the pawl 45 and the ratchet 46, cause the registering disk 47 to be advanced one number. A refund registering disk 50, having a smaller diameter than the disk 47 concentric therewith, is rigidly secured to the front end of the shaft 44 while a ratchet 51 is secured to the other end thereof, said ratchet 51 being adapted to be engaged by a pawl 52 on the 120 upper end of a second lever 53 loosely mounted upon the shaft 44, and is adapted to 125 be rotated by its pawl 52 in the opposite direction from that in which the disk 47 rotates, the purpose of which is, that when 130

one disk is partially rotated by its pawl it will be against the direction of rotation of the opposite disk so that one disk will not rotate the other by friction. The second lever 53 is operated by means of a connecting rod 54 which is in turn operated by the armature 55 of the coil 56, the said armature being returned to a normal position against the stop 57 by means of a suitable spring 58 when the said coil 56 is deenergized. The cover 2 is provided with a suitable window 60 having a suitable glass 61, said window 60 being so arranged that one numeral only on each of the registering disks 47 and 50 will be visible therethrough. The lower part of the curved portion 6 of the impressed slot in the frame 4 has an aperture 65 through which projects an insulated spring 64, the purpose of which will hereinafter be more fully described.

The operation is as follows: When a token V has been deposited and rests upon the pins 24 and 25, the said token closes a circuit which flows through the grounded battery 27 at the central office line 28, lamp 29, line 30, line 31, pin 24, token V, pin 25, lines 32 and 33, frame 4 and back to the ground. When the operator at central office is attracted by the light of the lamp 29, she makes the proper connections and if the party is obtained, presses the key 35 against the contact of the battery 36 which causes a negative current to flow to the line 37, line 30, coils 14 and 12 and line 33 to the grounded frame 4. This will cause the pin 24 to be withdrawn by means of the coil 12 and the token V will be deposited into the collecting portion of the slot and through the opening 7 of the frame 4 into the interior of the box.

If the light 29 is lighted by any other means than by the deposit of a token, that is, such as grounding the subscribers phone or short circuiting the line with the ground wire, a switch will be registered by the movement in either direction, of the armature 16 which operates the ratchet 46 by means of the connection 42 and pawl 45 and the next successive number on the said disk 47 will be displayed opposite the word "calls" at the window 60, when the operator energizes either coil 12 or 14 to refund or collect the token.

If a token V has been deposited and the desired connection is not obtained, the operator will press the key 35 so as to connect with the battery 36' which will cause a positive current to flow through the line 37, line 30, coils 14 and 12 and line 33 to the grounded frame 4. This will cause the coil 14 to attract the insulated pin 25, release the token V and drop the same into the slot 8 and receptacle 10. When the said token is released by the coil 14, as hereinbefore described, the said token in its passage to the

slot 8 closes the contact between the insulated contact 64 and the grounded frame 4. As the token V is released by contact of the key 35 with the battery 36' it will be observed, by referring to Fig. 8, that the current will also flow through the line 66, coil 56, line 67, contact 64 and the grounded frame 4, the token V closing the contact between the contact spring 64 and the said grounded frame 4. This will cause the coil 56 to attract the armature 55 and the connection 54 will then operate the pawl 52 and the ratchet 51 and cause the next successive numeral on the disk 50 to be displayed opposite the word "refund" in the window 60.

It is obvious from the foregoing that a switch will be registered against the subscriber whether or not a proper token is deposited. If the switch is not obtained the token releasing mechanism will register a switch and a refund if a token has been deposited. If no token has been deposited and the switch not obtained, the coin releasing mechanism will register a switch but no refund, consequently the subscriber will find it unprofitable to attempt to obtain a switch without depositing a proper token. The only way in which a refund, designating that the desired party can not be obtained, can be registered is by the passage of a suitable token which has been released by the operator at the central station.

Referring to Fig. 2 of the drawings, it will be observed that when a token V is resting between the pins 24, should other tokens be deposited in the slot 5, they will roll over the token between the pins 24 and 25 and close the contact with the frame 4. But the coil 56 and the refund disk 50 will not be operated thereby for the reason that the circuit will be open between the key 35 and the battery 36'.

Having thus described our invention what we claim as new and desire to secure by Letters Patent is—

1. In a call registering device for telephones, the combination with a token collecting box and the mechanism therefor, of a frame having a suitable slot therein arranged to receive a suitable token; an armature pivotally mounted upon the frame and insulated therefrom; pins secured to the said armature and projecting into the slot within the frame, one of the said pins being insulated from the armature; means operatively connected to the armature and arranged to display successive numerals when the said armature is attracted by either coils.

2. In a call registering device for telephones, the combination with a token collecting box and the mechanism therefor, of a frame having a token slot with a refund portion and a collecting portion therein; an armature pivotally mounted upon the frame and insulated therefrom; a pin secured to

each end of the armature and projecting into the slot within the frame, one of the said pins being insulated from the said armature; suitable coils arranged to attract the armature and to withdraw one of the pins; and registering means operatively connected to the said armature and arranged to register each movement of the said armature.

3. In a call registering device for telephones, the combination with a token collecting box and the mechanism therefor, of a frame having a token slot with a refund portion and a collecting portion therein; an armature pivotally mounted upon the frame and insulated therefrom; a pin secured to each end of the armature and projecting into the slot within the frame, one of the said pins being insulated from the said armature; suitable coils arranged to attract either end 20 of the armature and to withdraw one of the pins thereon; registering means operatively connected to one end of the said armature and arranged to register each movement of the said armature; and means for registering the passage of a token through the refund portion of the token slot.

4. In a call registering device for telephones, the combination with a token collecting box and the mechanism therefor, of a frame having a token slot with a refund portion and a collecting portion therein; a centrally pivoted armature mounted upon the frame and insulated therefrom; a pin secured to each end of the armature and projecting into the slot within the frame, one of the said pins being insulated from the said armature and arranged to release a token into the refund portion of the slot, the other pin being arranged to release a token into the collecting portion of the said slot; a disk rotatably mounted on the frame and having numerals successively arranged near the periphery thereof; a second disk rotatably mounted within the first mentioned disk and having successive numerals arranged near the periphery thereof; suitable coils arranged to attract one end of the armature and the pin thereon and release a token into the collecting portion of the token slot and partially rotate the first mentioned

disk when a current is passed through the said coils in one direction and to withdraw the insulated pin and release a token into the refund portion of the token slot and to partially rotate the first mentioned disk 55 when a current is passed through the coils in the opposite direction; and a coil arranged to be electrically connected with the current flowing through the first mentioned coils, by the passage of a token through the 60 refund portion of the slot, and to partially rotate the second mentioned disk.

5. In a call registering device for telephones, the combination with a token collecting box and the mechanism therefor, of a frame having a token slot with a refund portion and a collecting portion therein; a centrally pivoted armature mounted on the frame and insulated therefrom; a pin secured to each end of the armature and projecting into the slot within the frame, one of the said pins being insulated from the armature; suitable coils arranged to attract one end of the armature when a current is passed through the said coils in one direction and to attract the other end of the said armature when the said current is reversed; a registering disk rotatably mounted upon the frame; means operatively connected to the armature and adapted to partially rotate 70 the said disk with each movement of the said armature; a second registering disk rotatably mounted to the frame; a coil secured within the frame and adapted to partially rotate the second mentioned recording 75 disk when the said coil is energized; and means arranged to connect the said coil with the current flowing through the first mentioned coils when that pin is withdrawn which releases a token into the refund portion of the token slot.

In witness whereof we hereunto set our signatures in the presence of two subscribing witnesses.
